UNITED STATES PATENT OFFICE.

AUGUST SCHNAKENBERG, OF VOHWINKEL, NEAR DUSSELDORF, GERMANY.

PRESS FOR THE MANUFACTURE OF TUBES FROM MOLTEN METAL.

1,125,185.

Specification of Letters Patent.

Patented Jan. 19, 1915.

Application filed May 5, 1913. Serial No. 765,716.

To all whom it may concern:

Be it known that I, AUGUST SCHNAKENBERG, a subject of the Emperor of Germany, residing at Vohwinkel, near Dusseldorf, Empire of Germany, have invented certain new and useful Improvements in and Relating to Presses for the Manufacture of Tubes from Molten Metal, of which the following is a specification.

10 This invention is shown in the accompanying drawing.

It relates to presses for the manufacture of tubes, wires and the like from lead or other metal, wherein the metal is extruded by means of a piston by hydraulic pressure from the press-cylinder forming the mold; and the press-cylinder and the operating cylinder are arranged close behind each other. In presses of this kind, the press and 20 high-pressure water cylinders of which are connected together solely by means of a sleeve screwed on from the exterior, a distance-piece being arranged between them, there is the disadvantage, on the one hand 25 that the heat radiating from the liquid metal is transmitted to the water-cylinder through the metallic connecting parts by reason of the small distance away of the press-cylinder, which leads to inconvenience in many 30 ways, interruptions in working, etc., and on the other hand the interior of the press is shut off all around from the exterior by the sleeve and thus observation prevented in the event of any faults developing; it is also 35 difficult of access.

This invention has for its object to obviate all these disadvantages and consists in that the two cylinders are braced together by means of a distance piece provided with 40 openings (windows) which permits inspection of the interior of the press, provides for air-cooling and centers the two cylinders relatively to each other in the most exact manner.

45 The drawing shows a press for the manufacture of lead-tubes of small diameter, having one constructional form of my invention applied thereto.

Figure 1 shows the press in side elevation, 50 and Fig. 2 in longitudinal section.

1 is the thick-walled press-cylinder with a

nozzle 2 and die-orifice 3. The high-pressure water-cylinder or operating cylinder 4 has a piston 5, on the rod of which is the mandrel 6 that extends through the die-orifice.

7 is the supply-pipe for the high-pressure water, which enters the operating cylinder 4 beneath the piston and is provided with a controlling valve 8 and drain-pipe.

The juxtaposed ends of the cylinders 1 and 4 are provided with flanges 9 and 10. Between these flanges is arranged the distance-piece 11, which centers the cylinders and holds them at a constant distance from each other and has around its periphery apertures or windows 12, 12 arranged at uniform distances apart, the width of which is made such that they insure free inspection of and access to the interior of the press. 60 Against this distance-piece are tightly drawn the ends of the cylinders by means of screw-bolts 13, 13, which extend through smooth-walled holes 14, 14 in the flange 9 of the upper cylinder and their screw-threaded parts 15 are screwed into screw-threaded holes 16 in the flange 10 of the lower cylinder. The screw-bolts are made with capstan-heads 17 to enable them to be operated by means of a key. Instead of the annular 70 flanges the cylinders could obviously be provided with other suitable projections permitting their connection by means of screw-bolts or the like.

Having now particularly described and 85 ascertained the nature of my said invention and in what manner the same is to be performed, I declare that what I claim is:

1. In a press for the manufacture of tubes from molten metal, the combination of a hydraulic cylinder with a press cylinder, a piston in said hydraulic cylinder, a piston in said press cylinder rigidly interconnected with said first named piston, a mandrel connected with said second named piston, a distance piece inserted between said cylinders and bolts connecting the juxtaposed ends of the two cylinders.

2. In a press for the manufacture of tubes from molten metal, the combination of a hydraulic cylinder with a press cylinder, a piston in said hydraulic cylinder, a piston in

2
said press cylinder rigidly interconnected with said first named piston, a mandrel connected with said second named piston, a distance piece inserted between said cylinders 5 having a plurality of apertures, and bolts connecting the juxtaposed ends of the two cylinders.

Dated this 10th day of March 1913.
In testimony whereof I affix my signature
in presence of two witnesses.

AUGUST SCHNAKENBERG. [L. S.]
